UNITED STATES PATENT OFFICE.

WILLIAM G. STEVENSON, OF CHICAGO, ILLINOIS.

GRINDING-MILL.

1,345,714.

Specification of Letters Patent.

Patented July 6, 1920.

Application filed June 3, 1918. Serial No. 237,847.

To all whom it may concern:

Be it known that I, WILLIAM G. STEVENSON, a citizen of the United States, and a resident of Chicago, in the county of Cook and State of Illinois, have invented certain new and useful Improvements in Grinding-Mills, of which the following is a specification.

My invention relates to grinding mills, particularly to that type adapted for grinding material such as clay.

One of the important objects of the invention is to produce a machine of this type whose construction and arrangement makes its various parts more accessible for inspection, removal or repairs, and whose various parts, particularly the bearings, are fully protected against dust.

Another important object is to suspend the grinding pan or platform by means of a bearing at the top of the machine instead of supporting it from a step bearing placed in the pit of the machine as is the case in prior constructions.

Another important object is to provide short axles for the grinding rolls and improved means for journaling and guiding them.

The above and other features of the invention are embodied in a machine disclosed on the accompanying drawings in which—

Figure 1 is a side elevational view in greater part in vertical diametral section.

Fig. 2 is a plan view, partly in section on plane 2—2, Fig. 1, and having parts broken away and cover structures removed to more clearly reveal the construction.

Fig. 3 is a sectional view on plane 3—3, Fig. 2.

A rectangular pit 10 is formed by the foundation 11 usually of masonry, this pit having the lower outlet opening 12 which in practice is usually connected with a hopper 13 which leads to elevator mechanism for conveying the ground clay or other material to any place desired. Bridging across the top of the pit is an arch shaped frame structure 14 preferably in the form of a casting. Depending from the top of the casting arch

at the center thereof is an oblong frame part 15 forming a bearing pocket 16. The pan supporting shaft 17 extends axially in the pocket through an opening 18 in the base of the frame part 15. In the pocket 16 the shaft is received by the opposite bearing blocks 19 and 20 which are preferably lined

with friction-preventing material, such as Babbitt metal 21, abutment screws 22 and 23 serving to clamp the bearing blocks into snug bearing fit engagement with the shaft 17 and to accurately center the shaft axially in the pocket. Above the bearing blocks 19 and 20 is the annular seat or shoulder 24 on which are supported the bearing halves 25 and 26. The shaft has the section 27 of reduced diameter which is received by the bushing 28, this bushing having a series of annular peripheral flanges 29 engaging in annular bearing pockets 30 in the bearing halves 25 and 26, anti-friction material 31 being preferably interposed below the bearing flanges. The bushing 28 is clamped vertically between the shoulder 24 on the shaft and the collar 32 clamped around the section 27 of the shaft which is of less diameter than the shaft section 27 and the upper section 35 of the shaft. The shaft 17 is thus suspended by means of the bearing halves 25 and 26 engaging the shoulder 24. These bearing halves are prevented from rotating by the engagement of their rectangular lower lugs 36 and 37 with the parallel sides of the frame part 15, and also by the engagement of the rectangular upper lugs 38 and 39 with the parallel sides of a cap frame 40 surrounding the bearing and secured by its flanges 41 against the top of the casting 14. The lugs 38 and 39 also receive bolts 39' for clamping the bearing halves together. The upper end 35 of the shaft extends through the passageway 42 in the top of the frame 40 and is received between the bearing halves 43 and 44 secured to the top of the frame 40 by screws 45, the bearing halves having opposite lugs 46 and 47 for the bolts 48 which draw the halves securely around the shaft end, a bushing 49 being preferably interposed. To permit clamping together of the bearing halves the slots through which the screws 45 pass are elongated. The upper ends of the bearing halves 43 and 44 are preferably closed in order to guard against the entrance of dust. By means of the bearing blocks 19 and 20 and the bearing members 43 and 44 the shaft 17 is kept in axial alignment.

Suspended from the lower end of the shaft is the grinding pan supporting casting 50, the hub 51 extending upwardly at the center of the casting receiving the shaft to 110 be keyed thereto and to rest against the head 52. The annular frame 53 is secured

to the casting 50 and has the outer flange 54 for confining the annular cylindrical shell 55. The frame 53 has the annular discharge passageway 56 just within the flange 54, 5 the entrance to which passageway is covered by the screen 57. Between the passageway 56 and the hub 51 is laid the grinding plate 58 which is engaged by the grinding rolls. Surrounding the 10 frame 53 and secured thereto is the gear ring 59 with which the driving pinion 60 meshes. This pinion is secured to the lower end of a shaft 61 which extends through the lower and upper bearing frames 62 and 63 15 supported by the casting 14. The shaft at its upper end extends through a housing 64 forming the conical seat 65 for the hub 66 of the bevel gear 67 which is rigidly secured to the shaft. The cover 68 for the 20 housing 64 has the socket 69 for receiving the upper end of the shaft. Extending laterally into the housing 64 and journaled in the bearing 70 thereon is the transmission shaft 71 which within the housing has secured thereto a beveled pinion 72 which 25 meshes with the gear 67. The outer end of the shaft section 71 is journaled in the bearing 73 and terminates in a coupling member 74 which co-operates with the coupling member 75 secured to the shaft of the motor M mounted on the casting 14. The motor thus 30 provides the driving power for turning the pan structure.

Describing now the grinding roll mechanism, two rolls 76 and 77 are shown. As 35 best shown in Fig. 1, each roll is secured to a short shaft 78 by means of the split rings 79 and 80 of conical cross-section, the bolts 81 drawing the rings into wedging engagement between the conical sections of the 40 wheel and shaft respectively. Flanges or end plates 82 and 83 receive the shafts and engage against the sides of the roll and have pockets 84 for receiving the ends of the 45 bolts. The outer ends of the shaft are received by rectangular bearing caps or frames 85 and 86. These bearing caps extend into the rectangular frame enlargements 87 and 88 in each of which are the 50 opposed guide blocks or liners 89 and 90 which engage the sides of the bearing caps and prevent them from turning axially. Lateral displacement of the bearing caps is prevented by the cylindrical lugs 91 and 92 55 thereon which extend into the vertical grooves 93 and 94 formed in the liner blocks, the liner blocks being held in position by bolts 95. The grinder wheels rest on the plate 58 of the pan structure and crush 60 and grind the material charged into the machine as the pan structure is rotated, the rolls being free to move vertically. In order to prevent the heavy rolls from dropping in case the pan structure should break 65 or fall, U-straps 96 extend around the sides

and bottom of the frame enlargements containing the bearing caps, and these straps may be supported by the same bolts which hold the liner blocks in position. If, now, the pan structure is dropped or should 70 break, the rolls will be received and supported by the straps.

The openings 97 and 98 in the top of the casting 14 through which the rolls extend are provided with removable covers 99 and 75 100, respectively, and the upper ends of the various frame enlargements in which the roller bearings are housed have a removable cover 101. By removal of the covers the 80 rolls and bearing parts are readily accessible and when the covers are in place these parts are amply protected against dust and dirt.

Scraper structures are provided for guiding the material into the path of the rolls. 85 Two such scraper structures are shown, each comprising a frame body 102 supported by means of a bracket 103 fastened to the bottom of the casting 14 by bolts 104. The body part of each scraper supports the 90 outer, inner and intermediate blades 105, 106 and 107, respectively. These blades are supported by bolts and in order to provide for adjusting the blades the bolt holes 108 in the body 105 are elongated in one direction and the bolt holes 109 in the various 95 blades elongated in the opposite direction. The bolt holes are also so situated that the blades can be reversed. For example, on the outer blade 105 the lower outer corner 100 will wear most rapidly, and after such wear the blade can be turned around to present another corner. Likewise, the inner and intermediate blades can be reversed after they have become worn along one edge or corner. 105 To assist in holding the blade structures rigidly in position the outer ends of their bodies are connected by a turn buckle link 110 with the frame 14.

The scraper members are inclined in a 110 direction to shift the material to be ground into the path of the rolls, as shown in Fig. 2, the arrow indicating the direction of rotation of the pan structure. The material is fed onto the pan structure by means of a 115 chute 111 leading to the passageway 112 in the frame 14 which opens at its lower end above the pan structure, and as the pan structure rotates the material will be thrown outwardly by centrifugal force onto the screens, and the material which is already sufficiently fine will fall through the screen holes into the pit 10. The larger material will be deflected inwardly by the 120 scraper blades and directed to the rolls to be there ground, and this guiding action and the centrifugal force co-operate until all the material has been ground and discharged through the screens.

Where the material is ground fine consid- 125 130

erable dust will be raised but with my improved structure and arrangement all the bearing parts are well protected. The part of the pit not covered over by the frame 14 5 is covered by the plates 113 and 114. These plates and the various caps and covers for the bearing parts are readily removable so that inspection and repairs can be quickly and readily made. This covering of all the 10 parts insures safety as during operation of the machine it will be impossible for anything to fall into the machinery or for the operators to be injured. The machine is well balanced and efficient.

15 I do not desire to be limited to the exact construction and arrangement shown and described as changes are no doubt possible which would still come within the scope of the invention.

20 I claim as follows:
In a grinding machine of the class de-

scribed, the combination of a pit, a supporting frame bridging over said pit, a pan structure supported on said frame for axial rotation, said frame having vertical passageways therethrough, grinding rolls projecting downwardly through said passageways into engagement with the pan structure, vertical guide grooves in said frame for each passageway, journal boxes slidable 25 in said guide grooves, and a shaft for each roll having its ends extending into said journal boxes whereby said rolls may freely rotate and shift bodily vertically during operation of the machine, said guide 30 grooves being open at the top whereby each roll together with its shaft and journal boxes may be lifted through said passageways and removed from the machine.

In witness whereof I hereunto subscribe 40 my name this 29th day of May, A. D. 1918.

WILLIAM G. STEVENSON.
